CLAIM

The ornamental design for a medical imaging cart, as shown and described.

DESCRIPTION

FIG. 1 is a front perspective view of a medical imaging cart according to the claimed design.

FIG. 2 is a rear perspective view of the medical imaging cart.

FIG. 3 is a front view of the medical imaging cart.

FIG. 4 is a rear view of the medical imaging cart.

FIG. 5 is a right side view of the medical imaging cart.

FIG. 6 is a left side view of the medical imaging cart.

FIG. 7 is a top view of the medical imaging cart; and,

FIG. 8 is a bottom view of the medical imaging cart.

The broken lines immediately adjacent to the shaded areas depict the bounds of the claimed design, while all other broken lines are directed to environment. The broken lines form no part of the claimed design.

1 Claim, 8 Drawing Sheets
